UNITED STATES PATENT OFFICE.

JAMES L. ERSKINE, OF UPPER MONTCLAIR, NEW JERSEY.

DESIGN FOR A LATHERING IMPLEMENT.

46,208.

Specification for Design.

Patented Aug. 4, 1914.

Application filed April 2, 1912. Serial No. 688,067. Term of patent 14 years.

To all whom it may concern:

Be it known that I, JAMES L. ERSKINE, a citizen of the United States, residing at Upper Montclair, in the county of Essex and State of New Jersey, have invented a new, original, and ornamental Design for Lathering Implements, of which the following is a specification, reference being had to the accompanying drawing, forming part thereof.

Figure 1 of said drawing is a side view and Fig. 2 a top view illustrating said design.

I claim:

The ornamental design for a lathering implement as shown.

JAMES L. ERSKINE.

Witnesses:

I. MCINTOSH,
J. F. COLLINS.
